H. G. GILLMOR,
RAIL ANCHOR,
APPLICATION FILED APR. 11, 1918.

1,321,620.

Patented Nov. 11, 1919.

INVENTOR
H. G. Gillmor

UNITED STATES PATENT OFFICE.

HORATIO G. GILLMOR, OF WASHINGTON, DISTRICT OF COLUMBIA.

RAIL-ANCHOR.

1,321,620.

Specification of Letters Patent.

Patented Nov. 11, 1919.

Application filed April 11, 1918. Serial No. 227,932.

To all whom it may concern:

Be it known that I, HORATIO G. GILLMOR, a citizen of the United States, residing at Washington, in the District of Columbia, 5 have invented a new and useful Improvement in Rail-Anchors, of which the following is a specification, accompanied by drawings.

This invention relates to devices commonly known as rail anchors, rail stays or anticreepers and one of its objects is to provide a device which may be attached to or used with a tie plate and which will effectually prevent longitudinal movement of the 15 rail in either direction.

A further object is to provide an improved rail anchor in which the clamping or gripping engagement is with both the base and the head of the rail and is effected 20 through the instrumentality of a spring which is strained when applied to the rail so as to exert stress which will absorb vibration and take up looseness due to any cause. In a tie plate attachment for preventing creeping there is ordinarily contact between the attachment and the tie plate over a relatively small surface; and, on account of the wave movement which takes place in rails, there will be some movement of the attachment 25 in relation to the tie plate, which movement will in time result in wear of the softer part. The use of the spring in my invention prevents such wear from resulting in the loosening of the grip of the device upon the rail.

30 A further object is to provide a rail anchor which, while having the necessary strength will be very light in weight. Weight is an important consideration because of the saving in manufacturing cost and also in the 35 transportation of the anchors to the point where used.

The invention is illustrated, in one embodiment, in the accompanying drawings in which:

45 Figure 1 is a side elevation of the device shown as applied to a railroad rail, which is shown in section.

Fig. 2 is an end elevation of the device in its operative position on the rail, showing a 50 portion of one of the ties.

Fig. 3 is a side elevation, showing the rail in section, illustrating the method of applying the device to the rail.

55 Fig. 4 is a perspective view of the spring. Fig. 5 is a plan view of the rail base engaging shoe.

In the drawings similar letters apply to the corresponding parts in the several views.

Referring to the drawings, A represents the rail which rests upon a tie plate B, 60 which latter, in turn, rests upon a tie C, to which the rail and the tie plate are secured by spikes or screws D. The rail anchor, illustrated in the drawings as an attachment to the tie plate, consists, in addition to the 65 tie plate B, of two members E, Fig. 4, and F, Fig. 5. The member E consists preferably of a rectangular bar of steel which is bent to form two legs G and H, the ends of which may be rounded at I to conform to 70 the shape of that portion of the rail head with which this is to engage and at K to facilitate the placing of the spring in position. The member F is a shoe, which engages the upper surface of the rail base and 75 is provided with a flanged portion L, extending downwardly along the edge of the rail base. The middle portion of the member F is constructed with a seat M, which is arranged to receive the leg H of the member 80 E, each side of which are shallow flanges N, which guide the member E, while being forced into position and hold the leg H in position. The member F has also near the middle of its length and outwardly of the 85 seat M a heavy rib O, at the lower end of which there is provided the projection P, which is arranged to engage the aperture R in the tie plate B. This aperture R would ordinarily be one of the spiking apertures 90 with which all tie plates are provided. The projection P may have one or more of its faces tapered as at S in Figs. 1 and 3. The tie plate B may have a longitudinal rib U arranged to engage the edge of the rail base. 95

To place the device, the tie plate B is placed in position with the rib U engaging the edge of the rail base along the whole length of the tie plate and the shoe F is then placed with the projection P engaging 100 the aperture R in the tie plate B. The fit of the parts may be such that it will then be necessary to drive the projection P into the aperture R until the shoe F is in the position illustrated in Fig. 3. With the shoe 105 F in this position the spring E is placed with the rounded point K of the arm H engaging the seat M of the shoe F and the rounded end I of the arm G engaging the rail head. From this position to the final 110 operative position, the spring may be forced to move angularly, the rounded end I mov-

ing in contact with the rail head as if in a bearing, until the arm H is in contact with the seat or bearing M of the shoe F, as illustrated in Fig. 3. This forced angular movement will first force the shoe F down into contact with the upper surface of the rail base and cause the shoe to exert upon the tie plate B a transverse pull which will press the rib U against the edge of the rail base 5 with increasing pressure and will strain the spring, bringing the arms G and H nearer together. The relative position of the arms of the spring in the strained and the unstrained condition are illustrated in Fig. 4, 10 where the dotted lines indicate the position of the arms in the strained condition of the spring. In the final operative position of the parts, illustrated in Figs. 1 and 2, the spring E will be exerting a strong pressure 15 upon the shoe F and the shoe F will in turn be pressed downward upon the rail base and, at the same time, the shoe will exert a pull upon the tie plate B, which will press the rib U against the edge of the rail base. 20 The rail base will in this manner be firmly gripped between the tie plate and the shoe and the rail head will be gripped by the end of the arm G of the spring E. The pressure of the parts upon the rail will be determined by the pressure exerted by the 25 spring and by making the spring of suitable material and of the proper proportions this pressure may be made as great as may be desired. The spring and shoe will generally 30 be so proportioned and constructed that, with the parts in the operative positions shown in Figs. 1 and 2, the grip of the device upon the rail will be sufficient to effectually hold the rail and prevent creeping 35 movement. Should, however, this be not the case and some movement of the rail longitudinally in relation to the tie plate B occur, the end I of the arm G of the 40 spring E will be carried with the rail while the arm H will be held in the seat M of the shoe F by the flanges N; and the spring E will therefore assume one of the positions indicated by the dotted lines in Fig. 2. This 45 will automatically increase the pressure of the spring E upon the rail and the shoe and thus automatically increase the grip of the device upon the rail, so that the slight movement of the rail longitudinally will increase the grip of the device sufficiently to check 50 tendency to further movement of the rail; and this will be the case whether the rail moves in one direction or the other so that the device will be effective in preventing creeping movement in either direction. 55 Generally, rails are subject to a wave movement as the wheels of the rolling stock pass; and this wave movement will cause some vertical movement of the rail with respect to the tie plate. Such vertical movement will carry with the rail the shoe F and 60 65

will thus cause a sliding movement of the projection P of the shoe F in relation to the tie plate B. This movement in devices of this character is productive of wear of the softer part. It will be evident that in the 70 device here described such wear as may take place will cause slight lateral movement of the shoe upon the rail base and the arms of the spring E by opening out slightly adjust themselves to this lateral 75 movement of the shoe F with a slight reduction in the pressure exerted by the spring E upon the shoe and the rail; but without loosening the device upon the rail. The device is thus kept in effective gripping engagement with the rail even though there be considerable wear of the parts and the automatic tightening of the grip caused by slight longitudinal movements of the rail, 80 adjusts the grip to the conditions to be met 85 so that the rail is at all times effectually held against movement in either direction.

While I have described my invention in one embodiment, it will be understood that changes in form, construction and arrangement of parts might be made without departure from the invention. Therefore, I do not wish to be understood as limiting the invention to the exact construction described except so far as so limited by the 90 express language of the claims.

I claim and desire to secure by Letters Patent:

1. A part for anticreepers constructed of rolled bar bent to U form and arranged to 100 be forced in between the rail head and the upper surface of a rail base engaging element.
2. A rail anchor spring constructed with two arms, one of which is arranged to rotatably engage the rail head and the other of which engages a rail base engaging element. 105
3. A U shaped spring for rail anchors constructed to be forced in between the upper surface of a rail base engaging shoe and the rail head. 110
4. As a new article of manufacture, an anticreeping device for attachment to a tie plate, comprising a shoe constructed to engage the rail base and a tie plate and a rolled bar, bent to U shape, constructed to be forced in between the rail head and said shoe. 115
5. As a new article of manufacture, a tie 120 plate attachment for preventing rail creeping comprising a part constructed to engage the rail base and a tie plate and a spring constructed with two arms one of which is arranged to engage said part and 125 the other of which is arranged to rotatably engage the rail head.
6. As a new article of manufacture, a tie plate attachment comprising a part constructed to engage the rail base and a tie 130

plate and an element constructed to be forced in between the rail head and said part by transverse angular movement of said element about an axis adjacent the rail head.

5 7. As a new article of manufacture, an anticreeping device for attachment to a tie plate, comprising a rail base and tie plate engaging part and a spring constructed to be forced in between said part and the under 10 side of the rail head by rotation of said spring about an axis adjacent the rail head engaging portion of said spring.

8. A device for preventing the creeping 15 of rails, comprising rail gripping elements, one of which is a part engaging the rail base at one side of the rail and held in fixed position in the roadbed and one of which is a two armed resilient element arranged to be forced in between said part and the rail 20 head by rotation about an axis adjacent the rail head.

9. A rail anchor, comprising a holding 25 plate provided with means for engaging one side of the rail base and a fixed portion of the roadbed, a part engaging said holding plate and the rail base and a resilient element constructed to be forced in between said part and the rail head by angular movement about an axis adjacent the rail head.

30 10. An anticreeper, comprising a part provided with an abutment for engagement with the rail base at one side of the rail and with means for giving said part a fixed position in the roadbed in opposition to the 35 tendency of the rail to creep, a shoe arranged to engage said part and the rail base at the other side of the rail and a rolled bar bent to U shape and arranged to be forced in between said shoe and the rail 40 head.

11. A device for preventing the creeping 45 of rails, comprising a tie plate provided with means for engaging the rail base at one side of the rail, a part which engages the rail base and said tie plate at the other side of the rail, and a spring constructed to be forced in between the under side of the rail head and said part by rotation of 50 said spring about an axis adjacent the rail head.

12. A rail anchor, comprising a holding plate, a rail base engaging element and a U shaped bar engaging said element and the under side of the rail head and exerting 55 pressure thereon in tending to resume a shape from which it was sprung.

13. A device for preventing the creeping of rails, comprising a tie plate, a shoe engag-

ing said tie plate and the rail base and a bar, bent to form two arms, engaging said 60 shoe and the rail head so as to be rotatable about an axis adjacent the rail head and exerting pressure thereon in tending to assume a position from which it was sprung.

14. A device for preventing the creeping 65 of rails, including, in combination with the rail and a tie plate a part engaging the rail base and the tie plate and a two-armed resilient element so engaging said part and the rail head that it may be forced into 70 position by rotation about an axis adjacent the rail head and that longitudinal movement of the rail in relation to the tie plate and said part will cant said element and automatically increase the grip of the device 75 upon the rail.

15. An anticreeping device, including, in combination with the rail and a tie plate, a shoe engaging the rail base and said tie plate at one side of the rail and a spring 80 constructed with two arms so engaging said shoe and the rail head that it may be forced into position by rotation about an axis adjacent the rail head and that movement of the rail in relation to said tie plate will produce 85 angular movement of said spring and automatically increase the hold of the device upon the rail.

16. An anticreeper, comprising a holding 90 plate, a part constructed to engage the rail base and said holding plate at one side of the rail and a bar so engaging said part and the rail head that it may be forced in between the rail head and said part by angular movement about an axis adjacent the 95 rail head.

17. An anticreeper, comprising rail gripping elements engaging the rail base at opposite sides of the rail, a two-armed vertically disposed part rotatable about an axis 100 adjacent the rail head, engaging one of said elements and the rail head and means operative to give the lower portion of said vertically disposed part a fixed position in opposition to the tendency of the rails to creep. 105

18. A device for preventing the creeping 110 of rails, comprising two members engaging opposite sides of the rail base and a spring constructed with two arms and arranged to rotatably engage the rail head and one of said members, said members and said spring coöperating to give the lower portion of said spring a fixed position in the roadbed and to press said members against the rail base.

H. G. GILLMOR.
